US00D881612S

(12) **United States Design Patent** (10) **Patent No.:** **US D881,612 S**
(45) **Date of Patent:** **** Apr. 21, 2020**

(54) **CABINET**

(71) Applicant: **NEW-TEC INTEGRATION (XIAMEN) CO., LTD.**, Xiamen, Fujian (CN)

(72) Inventor: **Luhao Leng**, Fujian (CN)

(73) Assignee: **New-Tec Integration (Xiamen) Co., Ltd.**, Xiamen, Fujian (CN)

(**) Term: **15 Years**

(21) Appl. No.: **29/639,903**

(22) Filed: **Mar. 9, 2018**

(30) **Foreign Application Priority Data**

Sep. 29, 2017 (CN) 2017 3 0470872

(57) **CLAIM**

The ornamental design for a cabinet, as shown.

DESCRIPTION

FIG. 1 is a front view of a cabinet showing my new design thereof;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

(Continued)

The broken lines shown in the drawings are for the purpose of illustrating portions of the cabinet that form no part of the claimed design.

1 Claim, 7 Drawing Sheets
